FLUID OPERATED PUMP FOR WELLS

George Wallace Canfield, Menlo Park, Calif.,
Anglo-California Trust Company, a corporation,
executor of said George Wallace Canfield,
deceased

Application February 21, 1931. Serial No. 517,535

6 Claims. (Cl. 103—52)

This invention relates to a fluid operated pump particularly adapted for use in oil wells, deep water wells, and the like. The invention is primarily directed to a fluid operated pump in which air or other fluid under pressure is utilized.

The invention is also directed toward a method of pumping wells by the use of pressure fluid such as compressed air or gas, one of the characteristics of the method being that there is substantially no intermingling of pressure fluid and liquid being pumped.

In order to facilitate understanding of this invention, the invention will be more particularly described as it pertains to a pump for use in the recovery of oil from deep wells.

Although the use of compressed gases to facilitate the removal of oil from deep wells has been described heretofore and many devices employing the so-called gas lift method have been extensively used, the prior devices and methods have had several material disadvantages. In these prior systems and pumps, the pressure fluid or gas has generally been jetted into the body of oil in the form of fine bubbles so as to produce a mixture of oil and gas which, by reason of its buoyancy, is carried upwardly to the ground surface. Obviously, this method requires a very large volume of gas as compared to the volume of the oil recovery and the necessity of supplying such quantities of gas at the high pressures necessary in deep wells, entails expensive equipment and high operating costs. Furthermore, the number of variables encountered, such as pressures, character of the oil being handled, temperature changes, etc., render efficient operation very difficult and positive functioning of a gas lift almost impossible.

Furthermore, the necessity of handling a rather intimate mixture of gas and oil by these prior methods and devices, involves the use of tubing of larger size than would be required for oil alone. The jetting of gas into the oil body requires subsequently the use of special equipment for separating the gas from the recovered oil.

This invention in general has for its object the disclosure of a method whereby wells may be pumped by the use of compressed air or gas without encountering the difficulties experienced heretofore.

It is an object of this invention to disclose and provide means for pumping wells by means of compressed air or gas whereby the consumption of gas is minimized.

Another object of this invention is to disclose

and provide a fluid operated pump which is positive in action and efficient in operation.

Another object is to disclose and provide means for pumping oil wells with compressed gases wherein the gases are not intimately intermingled with the oil being recovered.

A still further object is to disclose and provide a fluid operated pump which is automatic in operation.

Another object is to disclose and provide a deep well fluid operated pump in which the variables of pressure changes and changes in character of the oil being handled are automatically compensated for.

Other objects, uses and advantages of this invention will become apparent from the following description of one preferred form of the apparatus, it being understood that the invention is not limited to the specific form described in detail hereafter but instead embraces all pumps or devices operating in substantially the same manner and embodying the invention herein-after disclosed.

In describing the invention, reference will be had to the appended drawing, in which:

Fig. 1 is a longitudinal section through a section of well tubing in association with the fluid operated pump embraced by this invention.

Fig. 2 is a transverse section taken along the plane indicated at 2—2 in Fig. 1.

Fig. 3 is a modified form of float which may be employed.

Fig. 4 is an enlarged longitudinal section taken through a portion of the valve control mechanism used in the pump shown in Fig. 1.

As shown in the drawing, the tubing 1 extending into the casing or into the liquid body within the well may be provided with a valve assembly generally indicated at 2. Said valve assembly may comprise a substantially circular body portion 3 adapted to be threaded connected as indicated at 4 and 5 to the tubing sections 1 and 6. The valve assembly 2 preferably includes two check valves adapted to successively act on fluid passing through said tubing so as to permit upward flow of fluid through the tubing and to check any downward flow.

As shown, the body portion 3 may be provided with transverse partitions 7 and 8, each one of said partitions including valve seats adapted to receive ball valves 9 and 10 respectively. For purposes of simplicity, transverse pins 11 and 12 are shown positioned above the ball valves 9 and 10 respectively for retaining said ball valves in operative relation with their seats. A laterally

extending port member 13 may be operatively connected to the valve assembly 2 as by means of the threaded connection 14, the laterally extending port thus formed preferably entering the valve assembly 2 at a point intermediate the check valves 9 and 10. The port member 13 may be connected as by means of a connecting member 15 with a cylindrical member 16 adapted to form a displacement chamber. The opposite end 10 of the displacement chamber 16 is preferably provided with a valve adapted to selectively connect the chamber 16 either with an exhaust port or with a source of pressure fluid.

As shown, the upper end of the displacement chamber 16 may be provided with a head 17 adapted to slidably receive a sliding valve 18 in a longitudinal bore 19 formed in the head 17. The bore 19 may be provided with a stop or shoulder 20 and with an adjustably positioned 20 stop 21 threadedly connected to the end of the head 17 as indicated at 22. The head 17 may be provided with an exhaust port 23 leading either to the space within the well and exterior of the tubing 1 or it may be connected by suitable conduit means, not shown, with the atmosphere or some point within the well above the position of the pump. The head 17 may also be provided with an inlet port 24 operatively connected as by means of a member 25 with a source 30 of pressure fluid such as compressed air or gas.

As shown, the connecting member 25 is adapted to place the intake port 24 in communication with a pressure fluid supply line 26 adjacent to the tubing 1 and leading to the source of fluid pressure, not shown, on the surface of the ground. The tubing 1 and the pressure fluid conduit 26 may be clamped together as by means of the clamping members 27 and 28 adapted to encircle the tubing 1 and the conduit 26, the clamping members 27 and 28 being held together in any suitable manner as, for example, by means of the bolts 29.

The valve member 18 slidably positioned within the bore 19 of the head 17 may be provided with suitable ports, as for example the ports 30 adapted to selectively place the chamber 16 in communication with either the exhaust port 23 (as is shown in Fig. 1) or with the source of pressure fluid through the intake port 24. The sliding valve member 18 may be provided at its lower end with a spider 31 having connected thereto a push rod 32 extending longitudinally through the displacement cylinder 16, the lower end of the push rod 32 being slidably carried in a guide member 33 attached or formed in the port member 13. The push rod 32 is preferably provided with stop members such as the stop members 34 and 35.

The push rod 32 between the stop portions 34 and 35 is preferably provided with a float or piston 36, which is loosely slidably carried on the push rod 32. As shown, the float piston 36 is provided with a central bore somewhat greater in diameter than the diameter of the push rod 32. The upper and lower faces of the float piston 36 may be provided with seats 37 and 38 around the central bore so as to permit the inclined stop members 34 and 35 to act as valves and become seated on the seats 37 and 38 respectively when the float piston 36 moves along the rod 32 into contact with said stop portions 34 and 35.

As shown in Fig. 1, the cylindrical surface of the float piston 36 is corrugated by means of a plurality of annular depressions 39, these corrugations tending to prevent the piston from sticking in the cylindrical displacement chamber 16.

The stop member 21 carried by the end of the head 17 may be provided with a mandrel 40 whereas the slide valve member 18 may be provided with a ring 41 carrying downwardly extending spring fingers 42 and 43 adapted to engage the head of the mandrel 40 when the slide valve 18 reaches the upper end of its stroke. 80

The device described hereinabove when placed in a well and preferably below the normal low or other liquid level within the well, operates as follows: The liquid will enter by means of the tubing 6 into the valve assembly 2 through the check valve 10. A portion of the liquid will rise into the tubing 1 through the check valve 9 while a portion of the oil or other liquid will pass out through the valve assembly 2 and port member 13 into the displacement chamber 16. The float piston 36 will thus be raised by the liquid until contact is made between the piston float valve seat 37 and the stop member 34 on the push rod 32. Further entry of liquid into the displacement cylinder 16 will cause the piston float 36 to rise and move the slide valve member 18, thus discontinuing the communication of the upper portion A of the chamber 16 with the exhaust port 23. 90

As the slide valve 18 moves upwardly, the yielding spring fingers 42 and 43 carried thereby slide over the mandrel 40 and retain the slide valve in position at its upper end of the stroke. Concurrently the ports 30 of the slide valve 18 form communication between the upper portion A of the displacement chamber 16 with the source of fluid pressure such as the conduit 26 through the intake port 24. The pressure fluid from the supply line 26 is thus permitted to act upon the upper surface of the piston float 36. The pressure of the pressure fluid in the line 26 is preferably sufficient to overcome the fluid pressure in the lower portion B of the chamber 16. The piston float 36 is thus forced downwardly displacing the fluid which had risen into the chamber 16 through the connecting member 15, port member 13 and check valve 9 into the tubing 1. 105

When the piston float 36 approaches the lowermost point of travel, it will contact with the stop 35, thus imparting longitudinal motion to the push rod 32 which in turn moves the slide valve member 18 out of engagement with the mandrel 40 causing the ports 30 of the slide 110 valve member 18 to again come into operative relation with the exhaust port 23. 115

It will thus be seen that substantially no intermixture of pressure fluid and oil or liquid being pumped, occurs in the displacement chamber 16 120 and that a volume of compressed gas will displace an equivalent volume of oil or other liquid. 125

Means such as the mandrel 40 and yielding spring fingers 42 and 43 maintain the slide valve in such position as to permit the pressure fluid 130 from the supply line 26 to act upon the float piston 36 and displace substantially all of the oil within the chamber 16. It is to be understood that any other equivalent means adapted to maintain the slide valve 18 immovable during the 135 movement of the float piston 36 may be used.

It is obvious that the depth from which oil may be pumped in the manner described hereinabove is only limited by the pressure of gas or air available. It is also obvious that a number of 140 these devices may be used at different levels along a single string of tubing, operating as a multiple stage installation whereby lower pressures may be employed. In such arrangement, the displacement chamber 16 would be spaced along the 145 150

length of the tubing at distances which the available pressure would raise the oil, the oil being thus passed from chamber to chamber until it reaches the surface.

5. Instead of employing the hollow float piston 36 shown in Fig. 1 any equivalent disc or piston may be used. As shown in Fig. 3, the float piston may comprise a plurality of spacer elements 50 suitably held together with flexible cup members 51 between said spacer elements, this assembly forming a piston provided with an inner bore adapted to loosely encircle the push rod 32. Furthermore, the stop members 34 and 35 may be adjustably positioned along the push rod 32 so as to permit accurate timing of the valve movement.

In cases where considerable gas pressure is produced in a well, such gas pressure being still insufficient to flow the well as in ordinary practice, the operation of the intake and exhaust ports 20 could be reversed allowing the chamber 16 to take gas for operation from the well casing itself and discharging the same to the surface through the gas transmission line. In other words, the line 26 could be operatively connected to the exhaust port 23 and the intake port 24 be permitted to take gas from the well casing.

Devices made in accordance with this invention lend themselves to easy and economical installation and operation. They are more reliable and uniform in operation than the customary gas lift and require much smaller volumes of compressed air or gas than prior devices. Furthermore, fluid operated pumps made in accordance with this invention handle more oil with the same size of equipment and are capable of accurate control to suit the maximum production of the well.

While the method and a particular form of apparatus for carrying out the invention has been described in detail, it is understood that the invention is not limited thereto but instead embraces all changes, variations and substitutions coming within the scope of the appended claims.

I claim:

45. 1. In a well pumping device, the combination of a straight string of tubing in a well hole, a valve assembly in said tubing, said valve assembly comprising two check valves adapted to successively act on fluid in said tubing to check any 105 downward flow, a vertically disposed displacement cylinder in parallel relation to said tubing, said cylinder being provided with a liquid conduit at its lower end in operative communication with said valve assembly at a point between said check valves, a pressure fluid line for supplying pressure fluid to the top of said cylinder, an exhaust port for the top of said cylinder, and a single means for alternately connecting said cylinder with the exhaust port and with said pressure fluid supply line, said means being actuated by change in liquid level within said cylinder.

2. In a well pumping device, the combination of a vertically disposed displacement cylinder, a liquid conduit in communication with the lower end of said cylinder, an upper head carried by said cylinder, means for supplying fluid under pressure to said head, an exhaust port in said head, a slide valve in said head and movable longitudinally of said cylinder, said slide valve being adapted to alternately connect said cylinder with said pressure fluid supply means and exhaust port, a push rod connected to said slide valve and longitudinally movable in said cylinder, stops carried by said push rod, and float means slidably carried on said push rod in said cylinder and

adapted to be moved by changes in liquid level in said cylinder and to contact with said stops to actuate said push rod and slide valve to selectively connect said cylinder with said means for supplying fluid under pressure and exhaust port.

3. In a device for pumping wells, the combination of a vertically disposed displacement cylinder, a liquid conduit in communication with the lower end of said cylinder, an upper head carried by said cylinder, means for supplying fluid under pressure to said head, an exhaust port in said head, a longitudinally movable slide valve in said head, said slide valve being adapted to alternately connect said cylinder with said pressure fluid supply means and exhaust port, a push rod connected to said slide valve and extending into said cylinder, stops carried by said push rod, a piston float slidably mounted on said push rod between said stops and adapted to be moved by changes in liquid level in said cylinder and to contact with said stops to actuate said push rod and slide valve to selectively connect said cylinder with said pressure fluid supply means and exhaust port, and yieldable means for holding said slide valve in communication with said pressure supply means.

4. In a well pumping device, the combination of vertically disposed tubing, a valve assembly comprising two check valves adapted to successively act on fluid to check any downward flow 105 carried by said tubing, a vertically disposed displacement cylinder, means for connecting the lower end of said cylinder with said valve assembly at a point between said check valves, an upper head carried by said cylinder, means for supplying fluid under pressure to said head, an exhaust port in said head, a longitudinally movable slide valve in said head, said slide valve being adapted to alternately connect said cylinder with said pressure fluid supply means and exhaust port, a push rod connected to said slide valve and extending into said cylinder, spaced stops carried by said push rod, and float means slidably mounted on said push rod between said stops and adapted to be moved by change in liquid level within said cylinder for actuating said push rod and slide valve by coming into contact with stops carried by said rod.

5. A device adapted to be inserted into well holes for pumping wells, consisting of a vertically disposed displacement cylinder, a single liquid inlet and outlet port in the lower end of said cylinder, means for supplying fluid pressure to the top of said cylinder, an exhaust port in operative communication with the top of said cylinder, a movable valve positioned in the upper end of said cylinder for alternately connecting said cylinder with the exhaust port and with said pressure fluid supply means, a rod attached to said movable valve, said rod extending axially through said cylinder, longitudinally spaced stops carried by said rod, and means slidably carried on said rod within said cylinder, said means being adapted to be moved by changes in liquid level within said cylinder into contact with said stops to actuate said rod and valve.

6. A well pumping device comprising a string of tubing adapted to be positioned in a well hole; a valve assembly carried by said tubing, said valve assembly including two vertically spaced check valves adapted to successively act on fluid in said tubing to check any downward flow therein; a displacement cylinder in parallel relation to said tubing and extending upwardly from the level of said valve assembly to a point there-

above; conduit means operatively connecting the lower end of said cylinder with said tubing at a point between said check valves; a head carried by the upper end of said cylinder, a pressure fluid line for supplying fluid under pressure to said head, an exhaust port carried by said head; movable valve means carried by said head, said movable valve means being adapted to alternately connect said cylinder with said pressure fluid line and said exhaust port; a rod attached to said

movable valve means, said rod extending axially through said cylinder, spaced stops carried by said rod; and means slidably carried on said rod within said cylinder, said means being adapted to be moved by changes in liquid level within said cylinder into contact with said stops to actuate said rod and valve means and admit pressure fluid into said cylinder. 80
